UNITED STATES PATENT OFFICE

155,175

DESIGN FOR A TOWEL HOLDER

Milton Marsh, Plainville, Samuel Goldreich, Middletown, and Louis C. Farley, Wethersfield, Conn., assignors to Raymond Products, Inc., Middletown, Conn., a corporation of Connecticut

Application February 6, 1948, Serial No. 144,326

Term of patent 14 years

(Cl. D33—16)

To all whom it may concern:

Be it known that we, Milton Marsh, Samuel Goldreich, and Louis C. Farley, citizens of the United States, residing respectively at Plainville, county of Hartford, Middletown, county of Middlesex, and Wethersfield, county of Hartford, State of Connecticut, have invented a new, original, and ornamental Design for a Towel Holder, of which the following is a specification, reference being had to the accompanying drawing, forming part thereof.

We claim:

The ornamental design for a towel holder, as shown.

MILTON MARSH.
SAMUEL GOLDREICH.
LOUIS C. FARLEY.
